United States Patent Office

Des. 178,650

Patented Sept. 4, 1956

178,650

VAULT ENTRANCE

Henry Dreyfuss, South Pasadena, Calif., assignor to The Mosler Safe Company, Hamilton, Ohio, a corporation of New York

Application February 3, 1955, Serial No. 34,349

Term of patent 14 years

(Cl. D69—1)

FIG. 1

I claim:

The ornamental design for a vault entrance, substantially as shown.
